[57] ABSTRACT

According to one aspect of the present invention a pedestal attachment is provided which includes a clip adapted to engage under the pedestal bridge to hold the attachment on the pedestal. The clip depends downwardly from a bottom wall which terminates at its rearward extremity in a low upright rear wall and a two-piece lid extends forwardly from a first hinge at the top of the rear wall. The lid includes a short rearward portion hingeably attached to a forward portion by a second hinge which is parallel to the first hinge. A pair of projections depend downwardly from the rearward portion for locking engagement in openings defined in the bottom wall. Pages having corresponding openings are held in the attachment by inserting the projections through the page openings.

3 Claims, 6 Drawing Figures

FIG. 6

FIG. 6

ATTACHMENT FOR TELEPHONE

This invention relates to an attachment for use on a telephone pedestal under the handset, the attachment including reference pages and being accessible upon lifting the handset off the pedestal.

Free-standing telephones have a pedestal and a handset which can be placed in a pair of saddles on the pedestal when not in use. A bridge between the saddles defines a rearwardly opening recess below the saddles to permit a person to insert his fingers in the recess when lifting the pedestal. A number of devices have been provided which fit into this recess to support pages of a memorandum pad, calendar or the like so that the user can refer to the pad as he uses the telephone. However, these devices have been unsatisfactory because they tended to fall off the telephone, and also because they prevented the user from inserting his fingers into the recess to lift the telephone.

According to one aspect of the present invention a pedestal attachment is provided which includes a clip adapted to engage under the pedestal bridge to hold the attachment on the pedestal. The clip depends downwardly from a bottom wall which terminates at its rearward extremity in a low upright rear wall and a two-piece lid extends forwardly from a first hinge at the top of the rear wall. The lid includes a short rearward portion hingeably attached to a forward portion by a second hinge which is parallel to the first hinge. A pair of projections depend downwardly from the rearward portion for locking engagement in openings defined in the bottom wall. Pages having corresponding openings are held in the attachment by inserting the projections through the page openings.

According to another aspect of the invention a pedestal attachment is provided which can be engaged on the bridge of a telephone pedestal whether or not the bridge includes an upwardly inclined forward portion.

According to yet another aspect of the invention an attachment for telephone pedestals is provided which includes a clip having an outer wall adapted to receive a double-sided adhesive pad for adhesive attachment to a wall mounted telephone and the like.

These and other aspects of the invention will be better understood with reference to the drawings in which:

FIG. 1 is a perspective view of a telephone pedestal showing an attachment according to the invention in place of the pedestal;

FIG. 2 is a side view of the attachment;

FIG. 3 is a rear perspective view of the attachment showing the underside of the attachment;

FIG. 4 is detail of part of the attachment; and

FIGS. 5 and 6 show the attachment in place on two different telephone pedestals.

Reference is first made to FIG. 1 which shows a conventional free-standing telephone pedestal 10 having saddles 12, 14 for receiving a handset (not shown). An attachment 16 is proportioned to fit snugly between the saddles 12, 14 and extends rearwardly to just within the rearward limits of the saddles. The front of the attachment 16 extends slightly beyond the front limits of the saddles to a position which facilitates using the attachment without interfering with either the saddles or the telephone dial 17. The top of the attachment is slightly below respective handset support surfaces 20,

22 of saddles 12, 14 so that the handset will rest on the surfaces 20, 22 rather than on the attachment 16. Although it is not evident in FIG. 1, the attachment contains pages for displaying advertising, calendars, note pages and the like. The structure of the attachment will be described with reference to FIGS. 2, 3 and 4 and then the pages will be introduced with reference to FIG. 5.

Reference is next made to FIGS. 2 and 3 which show 10 the attachment without the aforesaid pages in a closed position. This portion of the attachment is moulded from a suitable plastic such as polyvinylchloride and includes a bottom wall 18 having a generally horizontal main portion 20 and an upwardly inclined forward portion 22. A clip 24 is dependent downwardly from the bottom surface of the main portion 20 for releasably coupling the attachment to the telephone pedestal 10 (FIG. 1) as will be described with reference to FIGS. 5 and 6. A rear wall 26 extends upwardly from the rearward extremity of the bottom wall 18 and is connected by an integral hinge 27 to the rearward extremity of a two-part lid 28. The lid includes a short rearward portion 30 which is connected by an integral hinge 32 to a forward portion 34 of the lid 28. This hinge is weakened by an opening 33 along the hinge line to facilitate moving the forward portion 20 about this hinge.

Forward portion 34 is curved upwardly adjacent its forward end to match the shape of the bottom wall 18. 30 Lid 28 terminates at its forward extremity adjacent a pair of latch elements 36, 38 which are integrally attached to the bottom wall 18 and depend upwardly therefrom. Latch element 36 which is typical of both elements is shown in FIG. 4. The upward extremity of 35 element 36 includes a small inwardly-facing bead 40 which snaps over the side of the forward piston 34 of the lid 28 adjacent the forward extremity of the portion 34. A recess 42 is preferably formed in the side of the portion 34 to accommodate the thickness of the latch element 36 when the attachment is in the closed position shown in FIGS. 2 and 3.

The rearward portion 30 of the two-part lid 28 includes a pair of downwardly dependent projections 44, 46 each of which has an enlarged distal end for locking engagement on the underside of the bottom wall 18. A pair of openings are provided in the bottom wall for engagement by these projections. Once the projections are in place in the bottom wall, the rearward portion 30 of the two-part lid 28 is immobilized and upon opening the lid, the forward portion 34 pivots about hinge 32. The arrangement of hinges 27, 32 permits the attachment to be moulded and then assembled using only the projection 44 as will be described.

The clip 24 is of a relatively rigid construction for positive engagement on a telephone pedestal as will be described with reference to FIGS. 5 and 6. The clip 24 includes a pair of forwardly extending and parallel side walls 48, 50 which are attached to an outer wall 52, and these walls terminate at their forward extremities in a front wall 54. A pair of curved flanges 56, 58 depend transversely from respective side walls 48, 50 and a pair of locating ears 60, 62 project upwardly beyond the outer wall 52. These ears are integrally attached to the side walls 48, 50 and to the curved flanges 56, 58 to strengthen the clip in the region of the flanges 56, 58 and to locate a double-sided adhesive pad 64 on the outer wall 52. This pad can be used to adhere the at-

tachment to a wall, wall mounted telephone and the like.

The curved flanges 56, 58 are integrally connected to the bottom wall 18 and terminate remote from the wall for simplified moulding. It will be evident that because the clip is attached to the wall 18 both by rearward portions of the side walls 48, 50 and also by the flanges 56, 58, the clip is a relatively rigid structure.

A peripheral flange 66 extends across the upper portion of the front wall 54 and rearwardly along upper extremities of the side walls 48, 50 terminating at respective locking lugs 68, 70 adapted to lock the attachment to a telephone pedestal as will be described with reference to FIGS. 5 and 6. The flange 66 is tapered upwardly where it adjoins front wall 54 to facilitate engaging the attachment on a telephone pedestal.

Reference is next made to FIG. 5 which shows the attachment 16 in place on the pedestal 10. As seen in this view, the pedestal 10 includes a bridge 72 extending transversely between the saddles 12, 14 (FIG. 1) and having a rearward transversely extending rib 74. The previously described curved flanges 56, 58 are proportioned for locating engagement about the rib 74 with the lugs 68, 70 engaged against a forward extremity of the rib. Because peripheral flange 66 is curved upwardly at its forward extremity, the attachment can be engaged on the bridge 72 by pushing the attachment forwardly so that the flange 66 rides in the bridge and the clip and bottom wall separate to snap the clip over the rib 74. Once in place as shown in FIG. 5, the forward extremity of the clip is sufficiently removed from the rib 74 to ensure adequate gripping of the bridge 72. In the event that a person using the attachment tends to rotate the attachment in a clockwise direction (with reference to FIG. 5) the forward extremity of the clip 35 will cause the point of rotation to be at the front of the clip thereby limiting the possibility that the clip can be rotated off the bridge 72.

As seen in FIG. 5, pages 76 are included in the attachment and held in place between the bottom wall 18 and lid 28 by the projections 44, 46 which pass through openings prepared in the pages 76. The attachment is assembled by first positioning the pages on bottom wall 18 with holes in the pages in registration with corresponding openings in the wall 18 for receiving projections 44, 46. The lid 28 is then folded downwardly about hinge 27 to engage the projections 44, 46 through the pages and into the bottom wall 20. Assembly is completed by closing the lid over the latch elements 36, 38.

Lid 28 can be opened by simply forcing it upwardly out of engagement with the latch elements 36, 38, and closed by moving the lid downwardly to engage these latch elements. The form of the attachment is such that a telephone handset placed on the pedestal 10 will not contact the attachment 16. Also, once the handset is lifted off the pedestal 10, the attachment is readily accessible for reference to the pages.

Reference is next made to FIG. 6 which shows the attachment 16 releasably coupled to another type of telephone pedestal 78. This pedestal, together with the pedestal 10 constitute by far the major part of the telephone production of North America. The present attachment can be fitted on both pedestals.

The pedestal 78 includes a bridge 80 similar to the bridge 72 previously described. However, unlike the bridge 72, the bridge 80 depends rearwardly from an

inclined portion 82 which extends forwardly and upwardly. Also, a rib 84 at the rearward extremity of the bridge 80 is much smaller than the rib 74 of bridge 72. The attachment 16 is shaped to fit on the bridge 80 with the forward portion 22 of the bottom wall 20 snugly engaged against the inclined portion 82 of the pedestal 78. The lugs 68, 70 are proportioned to engage against the rib 84 so that although this rib is much smaller than rib 74, the clip nevertheless grips the bridge 80 firmly to locate the attachment 16 on the pedestal 78.

What I claim as my invention is:

1. An attachment for a telephone of the type having a pedestal and a handset, the pedestal including a pair of spaced-apart saddles each of which has a support surface for supporting the handset when the telephone is not in use, a bridge extending between the saddles below the support surfaces and defining a downwardly-extending rib at the rear thereof, the attachment comprising:

a bottom wall having a rear end, and in which a pair of openings are formed adjacent said rear end; a low rear wall extending upwardly from said rear end of the bottom wall and integrally attached thereto;

a lid extending forwardly;

a first hinge coupling a rear end of the lid integrally to the upper extremity of the rear wall; the lid including a short rearward portion, a longer forward portion and a second hinge joining the rearward portion to the forward portion, the second hinge being parallel to the first hinge, the lid further comprising a pair of projections downwardly dependent from the rearward portion and projecting through said openings in the bottom wall, the projections including enlarged distal ends in engagement with the bottom wall to retain the lid rearward portion in generally parallel relationship with the bottom wall;

pages positioned between the bottom wall and the lid and having openings therethrough, the projections passing through the openings in the pages to retain the pages in position, the pages being accessible by rotating the lid forward portion upwardly about the second hinge; and

a clip downwardly dependent from the bottom wall and adapted to lockingly engage the pedestal bridge with the clip located on the bridge rib, the attachment being proportioned such that when in place on the pedestal the attachment fits snugly between the saddles and below the handset support surfaces with the front of the lid positioned adjacent the telephone dial.

2. An attachment as claimed in claim 1 in which the lid forward portion and bottom wall include upwardly and forwardly inclined portions to facilitate positioning the attachment on a pedestal bridge of the type having a corresponding upwardly and forwardly inclined portion.

3. An attachment as claimed in claim 1 in which the bottom wall includes a pair of latch elements extending upwardly from sides of the bottom wall adjacent a forward end of the bottom wall, the latch elements being adapted to retain the lid in a closed position and being sufficiently resilient to permit opening the lid by applying an upward force to the lid.
